ELECTRON MULTIPLIER

Vladimir K. Zworykin and Jan A. Rajchman,
Philadelphia, Pa., assignors to Radio Corpora-
tion of America, a corporation of Delaware

Application June 10, 1938, Serial No. 212,890

1 Claim. (Cl. 250—175)

This invention relates to electric discharge devices and particularly to electron multipliers and has for its principal object the provision of improvements in the construction and operation 5 of photo-actuated electron multipliers.

The present invention is predicated upon an appreciation of the fact that photoemission and secondary emission are not directly related. Photosensitive electrodes, especially those of high 10 sensitivity, special spectral response, and low thermionic emission, are generally not good secondary emitters. The converse is also true, i. e., good secondary emitters are not always good photoemitters.

15 In a photo-actuated electron multiplier the preparation of a photoemissive surface necessitates the deposition of an alkali or other metal, the diffusion of which onto the multiplying electrodes is not always desirable. By way of example, if the multiplying electrodes are constituted of an alloy of gold or silver or copper and magnesium united in a thermodynamically stable alloy, as disclosed in the copending application Serial No. 197,994, filed March 25, 1938, of 20 Zworykin et al., their secondary emitting properties would be considerably altered if coated with an alkali metal or other photosensitive deposit. Furthermore, the presence of an alkali metal in the multiplying part of the device may cause 25 serious leakage and may lower the work function of the secondary emitting stages, thus giving rise to considerable undesired thermionic emission.

In this invention, the above-mentioned difficulties are obviated by dividing the tube into two 30 separate compartments, one of which contains the photocathode and the other of which contains the multiplying and output electrodes. The sole communicating channel between the two 35 compartments is an aperture in a tight partition or connecting tube. By means of a suitable electron optical arrangement, the electrons released from the surface of the photoemissive cathode are made to strike the first multiplying 40 electrode after they have passed through the aperture in the partition dividing the two compartments. If the rate of diffusion of the cathode metal vapor is small, a permanent slit or a very narrow connecting tube will prevent all 45 dis- 50 turbing effects. Otherwise, the aperture or the connecting tube can be closed during the process of activation of the multiplier and later opened to permit passage of the electrons. Various schemes for closing, covering or plugging the 55 aperture in vacuo will be later described.

Other objects and advantages, together with certain details of construction, will be apparent and the invention itself will be best understood by reference to the following specification and to the accompanying drawing, wherein

5 Figure 1 is a sectional elevation of a photo-sensitive electron multiplier constructed in accordance with the invention and wherein the cathode and multiplying electrodes are in separate compartments.

10 Figure 2 is a fragmentary sectional elevation of a modification of the device of Fig. 1, and

15 Figure 3 is a fragmentary sectional elevation of an electron lens system for focusing the photo-electrons upon the first multiplying electrode.

In Fig. 1, 1 designates an elongated highly evacuated preferably cylindrical envelope, the central longitudinal axis of which is marked x—x. A photocathode 2 is brushed, sprayed, or otherwise deposited on the inner surface of the 20 hemispherical end of 1, and later activated in situ as by caesium vapor admitted through the side seal 3. The emissive area of 2 may be limited to a circle viewed from the center of the sphere under an angle of 60° and, in any event, 25 is accessible to light rays from an external source exemplified in the drawing by a lamp 3 and lens 4.

A partition which may be of metal and may 30 comprise three planes 5a, 5b and 5c, fits tightly against the walls of the cylindrical envelope, as indicated at 6. The normal n—n to the central plane 5b of the partition preferably makes an angle of 60° with respect to the central axis 35 x—x of the main cylindrical portion of the envelope. The part 5b is provided with a circular or other shape orifice 7 in its center. The edge about 7 is preferably rounded and thickened as indicated at 7a to minimize cold emission.

The first multiplying electrode 10 has a dependent shield comprising two planes 10a and 10b forming a part thereof. A circular aperture 10c in the center of 10b is the directrice of a portion of a focusing cylinder 10d whose generatrices are parallel to the axis n—n. The 40 curved cathode 2, the apertures 7 and 10c and the focusing rings 7a and 10d constitute an 45 electron optical system having axial symmetry around the axis n—n.

The succeeding multiplying electrodes 11 to 50 55 19, inclusive, are of the general L-shape type described by Rajchman and Pike in copending application Serial No. 171,916, filed October 30, 1937. The illustrated cylindrical output electrode or anode 20 is similar to that described by 60

Snyder in copending application Serial No. 205,-
208, filed April 30, 1938.

As above described, the photocathode 2 is painted on the glass wall of the envelope. This 5 facilitates the usual alkali activation in that it permits a positive control of the surface under preparation. The alkali metal, which may be caesium, rubidium, potassium, or other substance which is the emissive equivalent of caesium, is introduced into the envelope in the form of a vapor through the side seal s. A door or gate 8 turning on hinges 8a may be used to close the aperture 7 during activation. Alternatively, and as described in connection with Fig. 2, the aperture between the compartments may be closed by a sphere (B, Fig. 2), which is afterwards removed from its seat in the aperture by tipping the tube. In this, or equivalent manner, the secondary electron-emitting electrodes 11 to 19 inclusive and the anode 20 are protected against the diffusion of caesium vapor from the compartment containing the photosensitive cathode.

The shield 10a, 10b, about the first multiplying electrode 10, electrically separates the axially symmetrical electron optical system, which comprises the cathode 2 and the small focusing cylinders or rings 7a and 10d, from the cylindrical system comprising electrodes 11 to 20, inclusive. One is thus able to more easily calculate in advance the relative design position and arrangement of the several multiplying electrodes.

Fig. 2 shows a tube 30 in which the part 31 containing the photoemissive electrode 32 is connected through a narrow tubulation 33 to the part 34 which encloses the multiplying electrode assembly. The part 31 has approximately a spherical shape. The inner surface of the base of the sphere 31 is metallized and constitutes a photocathode 32 whose shape is such as to focus the photoelectrons onto a multiplying electrode 35. The electrons from electrode 35 are focused onto electrode 40 by means of a cylinder or conduit 36 and a ring 37 in the shield 38 of multiplying electrode 40. The electron optical system comprising the cathode 32, electrode 35, cylinder 36 and ring 37 has axial symmetry. The electrode system including the multiplying electrodes 41 to 47, etc., is cylindrical, i. e. the equipotential surfaces are cylinders.

Electrode 40 has a shape capable of focusing secondary electrons onto electrode 41. The electrodes 41 to 47, inclusive, are similar to those described in connection with Fig. 1.

This embodiment (Fig. 2) of the invention is 55 of particular utility when the activation of the photo- and secondary-emissive surfaces necessitates, or is improved by, treatment at different temperatures. In this case, temperatures of compartments 31 and 34 can easily be controlled 60 independently. A ball B seated in the opening

of the conduit 36 provides an easy way of separating the compartments 31 and 34 during the activation of the cathode.

Electrode 35 and the photocathode surfaces 5 32 are similarly activated. This gives to electrode 35 a relatively poor secondary emission ratio. However, when caesium is employed, the secondary emissive ratio will be greater than unity and sufficient to ensure an electronic current of an intensity to actuate electrode 40. 10

The original electron stream may be controlled by means of auxiliary electrodes inserted in the said electron conduit and suitably energized. The control of the ultimate output current may thus be made much more sensitive than that resulting from control of the electron stream further along in the tube. 15

Fig. 3 shows such a modification of the invention. It represents in large scale the electron conduit of the device illustrated in Fig. 1 modified by the addition of two rings 50 and 51, the aperture 7 and ring 10d. The ring 50 has a high positive potential with respect to the partition 5 and may have the potential of any one of the early multiplying electrodes 10, 11 or 12. The 20 photocathode and the rings 7 and 50 constitute an electron lens system which focuses the photoelectrons through the electron conduit 7, 50, 51, 10d. By varying the potential applied to the ring 51 with respect to that of the photocathode, 25 electrons can be made either to strike the emissive surface of electrode 10 after passing through all of the lens elements, or else be made to turn back in the region ring 51 and be collected by and dissipated by the ring 50. 30

Other modifications of the invention will suggest themselves to those skilled in the art. It is to be understood, therefore, that the foregoing is to be interpreted as illustrative and not in a limiting sense except as required by the prior art and by the spirit of the appended claim. 35

What is claimed is:

An electron multiplier comprising an envelope having two evacuated compartments, a photosensitive cathode in one compartment, a plurality of multiplying electrodes in the other compartment, a wall of one compartment having an aperture therein which communicates with the other compartment, means comprising a plurality of electron lens elements mounted adjacent said aperture for focusing electrons from said cathode through said aperture and thence against one of said multiplying electrodes, and means mounted within the compartment which contains said multiplying electrodes for electrically shielding said electron lens elements from said plurality of multiplying electrodes. 55
